UNITED STATES PATENT OFFICE

EDMOND MOLLOY, OF PHILADELPHIA, PENNSYLVANIA.

RAILWAY-TRACK.

No. 900,188.

Specification of Letters Patent.

Patented Oct. 6, 1908.

Application filed October 31, 1906. Serial No. 341,366.

To all whom it may concern:

Be it known that I, EDMOND MOLLOY, a citizen of the United States, residing at the city of Philadelphia, in the county of Philadelphia and State of Pennsylvania, have invented a certain new and useful Railway-Track, of which the following is a specification.

This invention relates to railway tracks wherein the structure is intended to be installed permanently to afford a solid and substantial road bed for railway trains and for rolling stock generally.

The object of the invention is to provide a new construction in which the rails are held so firmly and securely in position that they will retain their alignment and be prevented from spreading. The new track may be laid or installed with ease, rapidity and economy, and when installed there is very little, if any, necessity for repairs, thus minimizing the expenses of maintenance connected with the road bed. Provision is made, also, for securing drainage of the track.

Broadly stated, the invention contemplates composite stringers or foundations for the chairs and rails of a track, such stringers or foundations forming permanent parts of the road bed or constituting the road bed itself.

According to one practical embodiment of said invention, the composite stringer or rail-foundation consists of a metal framework or a tubular structure, and an incasing material therefor, the latter being usually of concrete having cement as its principal ingredient, although such incasing material may be of any suitable nature. Furthermore, the metal framework or tubular structure is adapted to support or carry the chairs on which the rail is seated, and with said chairs coöperate means for clamping the rail to, upon or between the chairs.

In the accompanying drawings I have shown one embodiment of the invention, but the construction shown therein is to be understood as illustrative only, and not as defining the limits of the invention.

Figure 1 is a vertical cross-section through a roadbed constructed in accordance with this invention; Fig. 2 is a plan view of the track shown by Fig. 1; Fig. 3 is an elevation, partly in section, and on an enlarged scale, of one of the composite stringers of the present invention adapted for supporting one of the track rails; Fig. 4 is a vertical cross-section of the structure shown by Fig. 3; Fig. 5 is a

detail plan view of the structure shown by Figs. 3 and 4; Figs. 6 and 7 are perspective views showing one section or member of a chair, said views representing the respective ends of said rail-chair; Figs. 8 and 9 are detail views of a rail-clamp adapted to coöperate with a chair and a rail; Fig. 10 is a vertical cross-section through another embodiment of the invention, wherein there is employed a special form of chair adapted to support a bisected reversible and adjustable rail; and Fig. 11 is a detail perspective view of one of the members or sections of the rail-chair shown by Fig. 10.

In carrying this invention into practice the roadbed or foundation of the railway track is composed of longitudinal composite stringers A, B, adapted to support the rails C of the track, see Figs. 1 and 2. The composite stringers are banked with any suitable filling material to produce an embankment D, and between the rails of the track this embankment may be constructed or fashioned in order to provide a longitudinal gulley or gutter 80 d. From this gutter are adapted to extend transverse drains E, the latter running below one of the stringers and discharging the water from the gulley at any desired place away from the track.

For economy in construction and installation, the composite stringers A, B, are separate or installed individually, that is, they have no common connection, and they are only joined by the filling material which constitutes the embankment D. Each composite stringer consists of concrete, or similar material a, and metal b, for reinforcing said concrete, thus producing what I term "able-bodied concrete". In cross-section the 95 stringer A or B may have any suitable or desired contour, one form of said stringer being shown by Fig. 4. I may employ any suitable construction or arrangement of metal to form the internal strengthening member of the 100 stringer, but, in one embodiment of said invention, this metallic strengthening element is in the form of a skeleton framework, the same being shown by Figs. 3 and 4, as consisting of a framework which is triangular in 105 cross-section and composed of parts which are joined by coupling pieces. It is to be understood, however, that the invention is not restricted to any particular or detailed construction of the metal reinforcing member, 110 but it is believed that the particular form of the triangular skeleton framework is espe-

cially useful in the construction of the composite stringer. The base portion of the triangular framework is at the bottom of the stringer, and said framework has, at its apex, 5 a longitudinal runner b' , adapted for the reception of a plurality of chairs F for supporting the rail C .

Each chair F consists of the members or sections f, f' , one of which is shown more clearly by Figs. 6 and 7. The inner portion 10 of the chair section is provided with a transverse groove f^2 , and below this groove the chair section has a longitudinal passage or opening f^3 . The chair section is, furthermore, 15 provided with a longitudinal slot f^4 , the same being approximately T-shaped in cross-section, and opening through the upper face of the chair. A recess f^5 is provided on said upper face of the chair, said recess forming shoulders f^6 .

In the installation of the track, the members f, f' , of each chair are fitted to the runner b' of the metallic framework b , so that the grooves f^2 of said chair sections will embrace the aforesaid runner b' . The sections 25 of the chair are clamped firmly on the runner b' by a bolt G , which passes through the passages f^3 of said chair, and on the end portions of this bolt are screwed the nuts g , the latter 30 binding against the chair sections and clamping them firmly on said runner b' .

It will be understood that a suitable number of chairs F are attached to the runner b' of each framework forming a part of each 35 stringer, said chairs being spaced at proper intervals on the aforesaid runner b' , and said chairs being partly exposed above the concrete material a , for the proper reception of the rail C .

40 By reference to Figs. 3 and 4, it will be noted that the rail rests squarely upon the chairs and upon the concrete material a , in the intervals between the chairs, thus affording a permanent and substantial foundation 45 for the rail.

Any suitable means for holding the rail on the chairs may be employed, and in Figs. 8 and 9, I have shown different constructions of rail clamping devices. In Fig. 8 a wedge-shaped or tapered plate H is employed, said plate having, at its lower rear end, an offset or flange h , and said plate having a slot h' , which opens through one end of the clamp, thereby producing what I term a bifurcated 50 wedge or claw. In Fig. 9, another form of the clamp is represented at I , said clamp consisting of a tapering or wedge-shaped plate having a heel or flange i , and a slot i' . It will be noted that either of these clamps, H 55 or I , may be employed, as they are the mechanical equivalents one for the other. After the rail shall have been laid on the chairs, the clamps are fitted to said chairs and adjusted to engage with the base flange of the rail on 60 the respective sides thereof, and then the

clamps are secured in position by the bolts J , the heads of said bolts being received in the slots f^4 of the sections of the chair. The nuts j may be tightened on the bolts to force the clamps tightly into engagement with the 70 rail.

If desired, after the clamps have been placed in position, so that the heels thereof occupy the recesses of the chairs, the bolts may then be tightened, and thereafter the 75 clamps may be driven into place for the purpose of tightly clamping the rail upon the chairs. It will be understood that the heels of the clamps fit in the recesses f^5 of the chairs, so that the shoulder f^6 will prevent 80 the clamps from moving outwardly and away from the rail.

In installing a track in accordance with this invention one mode of procedure is as follows:—The grade being established, I 85 spread a layer of suitable material, such as cement concrete, in suitable proportions below the position to be assumed by each rail of the track. On this layer, and in correct position, the framework is placed, and another layer or charge of cement is then dumped upon the first layer so as to surround or envelop, substantially, the skeleton framework. On this layer a plank or board is placed on each side of the embryo stringer 90 so as to constitute a temporary form for the concrete material, thus enabling me to resume and complete the operation of installing the concrete material for the stringer. The concrete material is leveled off and accurately 95 finished so as to produce the permanent longitudinal composite stringer, and, at the proper time, the chairs F are fitted or applied to the member b' of the framework. As the top portion of the concrete material forming a part of 100 each stringer is intended to be somewhat above the upper sustaining member b' of the skeleton framework, I employ temporary twin blocks (not shown), which are the exact 105 counterpart of the chairs, said temporary 110 twin blocks being set in the cement, as well as fitted on the upper portion of the cement forms so as to be flush with the top. These temporary twin blocks are employed while the work of finishing and leveling the upper 115 portion of the concrete is in progress. As the concrete materials set and become hardened, the twin blocks are removed, and the members of the chair F are inserted on each 120 side of the composite stringer, said chairs engaging with the member b' of the skeleton framework, and being clamped firmly there-to, as heretofore described. It will be noted 125 that the members of the chair are partly embedded or incased by concrete material of the stringer, that said chair is clamped firmly to the member b' , and that the upper faces or seats of the chair are substantially flush with the accurately finished top surface of the concrete material.

In the embodiment of the invention shown by Figs. 1 to 5 inclusive, which represent a good substantial construction of reinforced concrete continuous dwarfed walls constituting the composite stringers, I have not shown, nor do I consider it necessary to show, the employment of the usual cross-ties in this structure. Nevertheless, provision may be made for such ties, should conditions 5 require them. I have shown, however, in Figs. 3, 4 and 5, one form of cross tie or cross connection between adjacent chairs on the parallel stringers. Said cross-tie or cross connection may consist of a length of tubular metal K. This cross-tie is received in the 10 projections k at the lower part of the chairs, and it is held or secured in place by any suitable means. The cross connection is intended to be incased or embedded permanently, as 15 at k', by concrete material, and this concrete material may have any desired form in cross-section, and it may be molded or formed by an appropriate mold or former which may be independent of the temporary former for the 20 stringers, or may be employed in conjunction therewith. It is evident that the cross-tie K may be inserted in the passages f³ of the chairs, in which event the bolts G may be omitted, and, in lieu thereof, the tubular 25 cross-ties J may be employed and another bolt K' may then be passed all the way through the tubular cross-tie fitting, the said bolt being fastened with the same nuts on the 30 outside of the walls a. This construction 35 provides a complete cross-tie connection at a very moderate cost, and it can be installed and protected from the weather by the concrete material quite expeditiously and economically.

40 From the foregoing description taken in connection with the drawings, it will be noted that the stringers are shown as oblong or square in cross-section for the reason that such a form of stringer or girder is well adapted 45 for supporting the rail-chairs, but it will be understood that the dimensions of the stringers or girders, and the size of the skeleton framework, may be modified and varied as conditions may require. In some instances 50 where an unusually strong stringer or girder is required, I prefer to employ a larger skeleton framework, the sustaining members whereof may be of solid iron bars, but, in any event, the skeleton framework will of itself 55 extend over fairly wide spaces and be self-supporting, while the operation of filling in the concrete material is being completed, so that the entire construction of the new roadbed can be perfected from end to end with 60 the same materials.

As hereinbefore indicated, the stringers or girders may be graded in any way familiar to, or preferred by, those skilled in railway track installation. As shown by Fig. 1, the embankment 65 may consist of good heavy soil or

other ballast, the space between rails can be utilized for water troughs, and said space can be well filled in and topped off with cement, as shown, so as to form said troughs, or to provide gulleys which may be drained advantageously by the transverse drain or by any other suitable construction. 70

In Figs. 10 and 11 of the drawings I have represented an embodiment of the invention wherein the composite stringer is used in 75 connection with a form of chair adapted for supporting a bisected and reversible rail, the latter being of the character disclosed in a prior application filed by me on March 20, 1905, Serial No. 251,181. As shown, the bisected rail C' consists of matching members which are recessed on their inner faces and are provided at their top and bottom edges with complementary rail heads, thus enabling the sections or lengths of the rail to be 80 reversed edge for edge, and end for end, for the purpose of presenting new wearing surfaces for engagement with the wheel flanges of the rolling stock. The sections of the chair F' are recessed on their inner faces to engage 85 with the side portions of the rail sections along the foot flange and the webs thereof, and these chair sections are, also, recessed on their inner faces for engagement with the stringer b' of the skeleton incased frame b. 90 The chair sections are, furthermore, provided with transverse openings or passages f³, in which are received the clamping bolts G', G², whereby the sections of the chair F' may be clamped firmly upon the member b' 95 of the framework, said bolts G', G², extending through the chair sections above and below the member b', respectively. 100

Having thus described my invention, what I claim as new, and desire to secure by Letters Patent, is:—

1. In a railway track, a stringer adapted to extend beneath a rail, lengthwise thereof, comprising a tubular metallic core or framework substantially triangular in cross section, and concrete material incasing said core or framework, and rail-supporting means connected to said core or framework. 110

2. In a railway track, a stringer adapted to extend beneath a rail, lengthwise thereof, comprising a tubular metallic core or framework substantially triangular in cross section, and concrete material incasing said core or framework, and rail-chairs each attached to a member of said incased core or framework. 115

3. In a railway track, a stringer adapted to extend beneath a rail, lengthwise thereof, comprising a longitudinal core composed of tubular metallic members united to produce a skeleton structure, and an incasing material for said tubular skeleton structure. 125

4. In a railway track, a stringer adapted to extend beneath a rail, lengthwise thereof, comprising a tubular skeleton framework substantially triangular in cross section, and 130

- 2
- a concrete material substantially enveloping said framework and co-extensive in length thereto.
5. In a railway track, a stringer adapted to extend beneath a rail, lengthwise thereof, comprising a longitudinal metallic core composed of tubular metal united to produce a skeleton framework substantially triangular in cross section, incasing material substantially enveloping said core or framework, and rail-chairs secured to said core or framework and positioned externally with respect to said incasing material.
6. In a railway track, a stringer adapted to extend beneath a rail, lengthwise thereof, comprising a longitudinal metallic core composed of longitudinal and transverse members of tubular metal united to produce a skeleton framework, incasing material substantially enveloping said core or framework, and rail-chairs secured to said longitudinal tubular member of the core.
7. In a railway track, a longitudinal member incased in suitable material, and a sectional chair clamped to said member.
8. In a railway track, an incased member, and a sectional rail-chair supported by said member.
9. In a railway track, an incased core having longitudinal and transverse tubular metallic members united to produce a skeleton structure, the openings in which are filled by the incasing material, and rail-chairs carried by one of said longitudinal tubular members.
10. In a railway track, a longitudinal member, a rail chair adapted to be clamped to said member, a rail holding device carried by the chair, means for clamping said rail holding device to said chair, and independent means for clamping said chair to the aforesaid longitudinal member.
11. In a railway track, a longitudinal framework, incasing material therefor, and a plurality of rail-chairs supported by said framework.
12. In a railway track, a longitudinal framework, incasing material therefor, and a plurality of rail-chairs supported by said framework, said rail-chairs being exposed relative to the incasing material and adapted to coöperate therewith in supporting a rail.
13. In a railway track, a longitudinal framework, incasing material therefor, recessed rail-chair members fitted to the framework, and means for clamping said members on said framework.
14. In a railway track, a longitudinal framework, incasing material therefor, a plurality of rail-chairs supported by said framework, and rail-engaging devices carried by each chair.
15. In a railway track, a skeleton framework, incasing material forming with said framework a longitudinal stringer, chairs carried by the framework, rail-clamps on the chairs, and means for adjustably fastening said clamps to the chairs.
16. In a railway track, a metallic framework substantially triangular in cross-section, incasing material for said framework, and rail-chairs supported by the framework at the apex of the triangular part thereof.
17. In a railway track, adjacent stringers each having a framework and incasing material therefor, rail-chairs on the frameworks, and cross connections between adjacent chairs.
18. In a railway track, adjacent stringers each having a framework and incasing material therefor, rail-chairs on the frameworks, and incased cross connections between adjacent chairs.
19. In a railway track, adjacent stringers each having a framework and incasing material therefor, rail-chairs on the framework, and cross connections incased by the incasing material and connecting adjacent chairs of the frameworks.
20. In a railway track, longitudinal stringers each comprising frameworks enveloped by incasing material, rail-chairs on the stringers, and metallic connections attached to the adjacent chairs, said connections being enveloped by the incasing material.
- In testimony whereof I have subscribed my name to this specification in the presence of two witnesses.
